UNITED STATES PATENT OFFICE.

HUGH HENRY, OF ENNIS, TEXAS.

BUCKSAW.

SPECIFICATION forming part of Letters Patent No. 651,757, dated June 12, 1900.

Application filed May 17, 1899. Serial No. 717,166. (No model.)

To all whom it may concern:

Be it known that I, HUGH HENRY, residing at Ennis, in the county of Ellis and State of Texas, have made certain new and useful Improvements in Bucksaws, of which the following is a specification.

My invention is an improvement in buck-saws, seeking to provide a simple construction whereby to secure the saw-blade detachably in position and to tighten the same to any desired degree for operation; and the invention consists in certain novel constructions and combinations of parts, as will be herein-after described, and pointed out in the claim.

15 In the drawings, Figure 1 is a side view of the saw ready for use. Fig. 2 is a detail view of the handle portion with the blade and loop-frame detached. Fig. 3 is a detail view of the loop-frame. Fig. 4 is a detail view of the saw-blade detached, and Fig. 5 is an edge view of the outer end of the saw.

The loop-frame A is formed with the top bar B, having at its outer end the bar C, the latter forming one of the end bars of the saw-frame, of which the handle D forms the other end bar. This handle D is formed with a metal plate E and the wooden bars E', covering the same, and at its upper end the bar E is prolonged to form or is otherwise provided 25 with the arm F, which is extended forward over the top bar of the loop-frame and is detachably connected therewith by means of the loop G, which slides along the top bar B into and out of engagement with the arm F, being adapted at its upper side to engage in 30 notches F' on the arm F.

The top bar B of the frame A is pivoted at B' to a lug E², projecting forward from the bar E, and a similar lug E³ projects forward 40 from the bar E and is provided with an undercut bearing for engagement by the saw-blade. This bearing is preferably a stud I, undercut at I', and a similar stud C² projects laterally from the bar C near its free end.

45 The saw-blade K is provided near its ends with openings K' to fit over the studs I and C², so that the saw-blade can be held in the under-cut portions of such studs when the latter are forced apart in the operation of 50 tightening the blade.

In operation the arm F has a slight spring or elasticity, so that it will permit the adjustment of the loop or connecting-ring over the end of such arm and along the same to tighten the saw-blade to any desired degree. When it is 55 desired to remove the saw-blade for sharpening or for any other desired purpose, it is only necessary to press the arm F slightly toward the bar A and slip the ring or loop G off the free end of the arm F, when the studs I and C² may be adjusted slightly toward each other to permit the removal of the blade. The blade may be replaced on the studs I and C² when desired, and the saw be again adjusted for use by slipping the loop G over the end 60 of and up along the arm F to any desired position. It will be noticed the arm F inclines upward from its free end, so that the saw may be tightened to a greater or less extent by adjusting the loop G along the said arm as 65 may be desired.

It will be noticed that I avoid the use of all threaded straining-rods and provide a device for exerting tension which is simple, readily operated, and is not likely to get out 75 of order.

By means of the lever-arm F in the sliding-ring G, I am able to exert great power in tightening the saw-blade. The construction of the bar E, with the lugs forming a pivot for 80 the top frame and a support for the lug I and the lugs I and C², forms a convenient means of connection of the saw-blade and avoids the necessity of rivets or similar removable fastenings.

Having thus described my invention, what I claim as new, and desire to secure by Letters Patent, is—

A bucksaw comprising the frame having the top and end bars, the handle-bar pivoted 90 to the top bar and having a lever-arm extended thereover and provided in its upper side with notches, the sliding loop or ring fitted over the top bar and lever-arm and engaging the notches in the latter and the saw-blade 95 substantially as set forth.

HUGH HENRY.
